UNITED STATES PATENT OFFICE.

ARTHUR B. REID, OF CHICAGO, ILLINOIS.

TYPE-WRITING MACHINE.

SPECIFICATION forming part of Letters Patent No. 415,063, dated November 12, 1889.

Application filed January 19, 1889. Serial No. 296,909. (No model.)

To all whom it may concern:

Be it known that I, ARTHUR B. REID, a subject of the Queen of Great Britain, residing at Chicago, in the county of Cook and State of Illinois, have invented a certain new and useful Improvement in Type-Writing Machines, of which the following is a specification.

In operating a type-writing machine the operators are frequently compelled to use erasers and pencils, and it is an indisputable fact that considerable time is wasted in taking such articles from the places where they are usually kept and in replacing the same.

Type-writing machines as constructed prior to my invention are usually arranged upon stands or tables; but, in view of the fact that the spaces of said stands or tables both to the right and to the left of the type-writing machines are used for manuscripts and copies, it has been common with operators to keep such articles as erasers and pencils either within a drawer under the top of the stand or at some other rather remote point.

The object of my invention is to avoid unnecessary delay in the work of copying upon type-writing machines, to provide means whereby lead-pencils, erasers, and the like may be within ready and convenient reach of the operator, and to provide certain improved details of construction; as hereinafter set forth.

My invention may be applied to any or all constructions of type-writing machines, but will be readily understood from the following description in connection with the accompanying drawings, wherein I have selected the frame-work or body-frame of two different styles of type-writing machines, the one being commonly known as the "Remington" and the other as the "caligraph." To the body-frame of either of said styles of type-writing machine or to the body-frame of other known or suitable constructions of type-writers I apply a rack or holder mainly adapted for lead-pencils and erasers, but preferably further adapted for holding other articles, such, for example, as paper-fasteners, rubber bands, and other similar articles or stationery commonly used by the operators on type-writing machines. The precise location of said rack or holder, which may be termed

a "stationery-rack," will be somewhat dependent upon the shape and construction of the body-frame of the machine, it being observed that in each instance I propose arranging the stationery-rack in a position where it shall not only be well available to the operator, but also in a position where it will not interfere with the operation of the machine or with the free use of the operator's hands in operating the keys.

In said drawings, Figure 1 represents in perspective the main or body frame of a style of machine commonly known as the "Remington" with my invention applied thereto. Fig. 2 represents my invention applied to the main or body frame of a type-writing machine commonly known as the "caligraph," which said frame is shown in perspective. Fig. 3 represents in perspective a stationery-rack adapted for application to a type-writing machine and embodying certain features of my improvement.

In Fig. 1, A indicates the body-frame of a type-writing machine provided with a stationery-rack B, which said rack is arranged in a vertical position substantially between the two front posts or standards a. The rack B thus arranged in a Remington machine will be back of the set of keys, which, as is well known, are arranged within the space a' at the front of the machine. While said rack can be supported in various ways, a simple and convenient way of attaching it to the machine will be to provide said rack with spring clips or fingers b, which can be caught upon the horizontal bar a', that extends from one to the other of the said front posts a.

The rack B, as shown in Figs. 1 and 3, consists of a sheet-metal plate b', which is bent along its lower edge portion, as b², so as to provide a trough b³. Said trough can be divided by partitions b⁴ into several compartments, and may also have end plates b⁵, so as to complete the two end compartments and prevent matters from dropping out. Said compartments may be used for containing paper-fasteners, rubber bands, pins, and the like. The plate b' is also provided with one or more shelves or troughs b⁶, which may be closed at either end and employed for holding pencils, erasers, and the like. The spring-

fingers *b* may, as an exceedingly simple construction, be formed by cutting them from the body-frame of the plate *v*.

In Fig. 2 the body-frame *C* of the type-writing machine has in front of the place where the keys are arranged an inclined surface *c*, as is well known to all familiar with the calligraph-machine. In a machine of such character a rack *B* can be arranged across the surface *c* of the body-frame, as illustrated in said Fig. 2, whereby, while the operator can conveniently take articles from the rack and also replace them in the rack after use, said rack will in no wise interfere with the free movement of the arms and hands of the type-writer.

From the foregoing description the principles of my invention will be readily understood, and it will be understood without further illustration that in certain old constructions of type-writing machines the racks *B* may be properly and conveniently applied to the side of the machine in place of being arranged at the front thereof, as herein illustrated.

So far as I am aware a type-writing machine has never been provided with a stationery-rack, and it will be evident that by my invention the serviceability of the machine will be increased, since great saving in time will be effected. This will be appreciated by type-writers, who so frequently upon striking a wrong letter or misspelling a word stop working the machine and pick up an eraser for the purpose of erasing the misprint in order that the correction may be made by again working the machine so as to type-write such correction, and on the other hand type-writers frequently, in place of making

such correction by erasure, make the same in pencil, and also frequently make certain notes which they propose referring to after taking the work out of the machine.

The series of troughs or shelves shown in Fig. 3 can be closed at their ends by separate end plates, or but two end plates can be provided for the entire series of shelves or troughs, each plate being, for example, to take the place of three end plates, such as herein shown.

The rack *B* can be provided with troughs or compartments by simply corrugating a piece of sheet metal, and obviously such rack can be readily shaped in outline for other styles of machine—such, for example, as the Hammond type-writer.

What I claim as my invention is—

1. The body-frame of a type-writing machine provided with a stationery-rack, as set forth, said rack being arranged with relation to the body-frame of the machine and the keys thereof substantially as described, so as to be within ready reach of an operator who may be working the machine.

2. A stationery-rack for a type-writing machine, consisting of a plate provided with receptacles such as set forth and adapted for application to the body-frame of a type-writing machine, substantially as and for the purpose described.

3. The herein-described stationery-rack provided with shelves and compartments and constructed with the spring-fingers *b*, substantially as and for the purpose described.

ARTHUR B. REID.
